FIG. 5

INVENTOR.

JAMES A. MURPHY.

BY

Lockwood Lockwood
ATTORNEYS.

UNITED STATES PATENT OFFICE.

JAMES A. MURPHY, OF CONNERSVILLE, INDIANA.

AUTO HEATER.

Application filed January 16, 1922. Serial No. 529,487.

To all whom it may concern:

Be it known that I, JAMES A. MURPHY, a citizen of the United States, and a resident of Connersville, county of Fayette, and State of Indiana, have invented a certain new and useful Auto Heater; and I do hereby declare that the following is a full, clear, and exact description thereof, reference being had to the accompanying drawings in which like numerals refer to like parts.

This invention relates to an auto heater for self-propelled vehicles wherein air is heated by the engine and particularly the exhaust thereof.

15 The chief object of the invention is to provide a heating system of the character indicated, wherein complete control of the heating medium and the heated medium is obtained.

20 Another object of the invention is to provide means for positively insuring the circulation of the heated medium.

In addition to the accomplishment of the foregoing objects, an additional feature consists in by-passing a portion of the exhaust gases to and through a turbine unit to derive power for operating a fan in the heated medium system.

Another feature of the invention consists 30 in the association of the muffler or condenser in the exhaust line of an engine with a heater housing included in the heated medium system.

Other features of the invention will be 35 pointed out in detail in the following specifications.

The full nature of this invention will be understood from the accompanying drawings and the following description and 40 claim.

In the drawings Fig. 1 is a top plan view of an engine propelled vehicle showing parts of the invention therein by full and dotted lines. Fig. 2 is an enlarged elevational view of the heating and heated medium systems. Fig. 3 is an enlarged side elevational view of the combination muffler and heater housing together with the fan and turbine, parts of the latter being broken 45 away to show in section other parts in detail. Fig. 4 is an enlarged front view of the construction shown in Fig. 3. Fig. 5 is a side elevation of a modified form of the invention wherein the fan and turbine has 50 been omitted and is similar to Fig. 3.

In the drawings 10 indicates an engine

propelled vehicle in the form of an automobile having an engine 11 therein and of the internal combustion type. The exhaust gases from the engine are discharged 60 through an exhaust pipe 12 which communicates with a muffler construction 20, which in turn communicates with a tail pipe construction 14. The motor vehicle is shown provided with forward and rear seating 65 compartments 15 and 16 respectively, and in each of said compartments there is positioned a register 17. Each register is connected by the pipe 18 to the construction indicated generally by the numeral 13 in 70 Fig. 1.

Reference will now be had to Figs. 2, 3 and 4 and in said figures the muffler itself is indicated generally by the numeral 20. Said muffler is substantially cylindrical in 75 form and the several details thereof are illustrated and described in a co-pending application Serial No. 482,158 filed July 2, 1921. The muffler 20 is provided with an intake 21 which is adapted to receive the 80 exhaust pipe 12, see Fig. 2. Interposed in the exhaust pipe 12, before it projects into the intake 21, is a cut-out construction indicated generally by the numeral 22. The details of said cutout are shown clearly in 85 Fig. 5, and comprise a pivotally supported valve 23 which is maintained in the closed position by a pivotally supported lever 24. When the lever 24 is rocked upon its pivotal support, the valve 23 opens, due to gravity, 90 and the exhaust discharges through an opening normally closed by the valve 23. Thus the exhaust discharges from the pipe 12 without going through the muffler in the usual manner. Any other form of cut-out 95 may be substituted for that herein disclosed without departing from the broader features of the invention. The muffler 20 likewise is provided with a discharge 25 which connects with the tail pipe 14 in the 100 usual or in any preferred manner.

Entirely surrounding the cylindrical muffler 20 is a heater housing 13 which is spaced therefrom, as shown clearly in Figs. 3 and 4. The heater housing is provided with a partition 26 and the air which is received by the housing is caused, by said partition, to engage the muffler before being discharged from the housing. Herein the housing 13 is provided with an intake opening 27 and a 105 pair of oppositely directed discharge openings 28. The oppositely directed discharge

openings 28 discharge into the conduits 18, which supply the registers 17 with heated air.

The housing 13 is provided with an auxiliary intake chamber 29 which has an opening 30 therein. The intake chamber 29 communicates with the housing 13 and positioned in said chamber 29 is a suitable fan or impeller 31 mounted upon a shaft 32. The shaft 32 extends transversely across and in front of the housing 13 and upon the opposite side of said housing is positioned a turbine construction 33. Upon the shaft 32 which extends into the turbine housing 33, is mounted a turbine wheel 34 having the blades 35 thereon. A conduit 36 forms a nozzle discharge adjacent the blades and an extension thereof forms a discharge 37 from said blades. Interposed between the cut-out member 22 and the intake opening 21 of the muffler 20 is a by-pass conduit 39 which includes a valve 38 interposed between the junction of the by-pass 39 with the exhaust pipe 12 and the turbine nozzle 36. A discharge pipe 40 connects the exhaust 37 of the turbine construction with the pipe 14, as shown in Figs. 2 and 3 thereby by-passing the muffler 20 and providing for a greater difference in pressure, thereby making available a greater difference in pressure than would be obtained if the conduit 40 discharged into the muffler. Thus the exhaust

gases are adapted to operate the turbine, which in turn is adapted to rotate the impeller and positively circulate the air by drawing the same into the chamber 29 and forcing the same through the heater housing into the conduits 18.

In Fig. 5 there is illustrated a modified form of the invention in which the auxiliary intake chamber 29 has been omitted, together with the turbine construction 33. Otherwise the modification shown in Fig. 5 is substantially the same as that shown in Figs. 3 and 4.

The invention claimed is:

In a self-propelled vehicle, the combination with an internal combustion engine having an exhaust pipe for discharging exhaust gases, of a muffler connected with said exhaust pipe adapted to be heated by the discharge of the gases therethrough, an air containing housing surrounding said muffler and deriving heat therefrom, a passage connecting said housing with the interior of said vehicle, a by-pass connected with the exhaust pipe, and means operable by the exhaust discharged through said by-pass from said engine for positively circulating the air from the housing to the vehicle.

In witness whereof, I have hereunto affixed my signature.

JAMES A. MURPHY.
